UNITED STATES PATENT OFFICE.

JOHN W. HUNTER, OF ENGLEWOOD, MISSOURI.

CONCRETE-FORM.

1,121,840.

Specification of Letters Patent. Patented Dec. 22, 1914.

Application filed July 21, 1913. Serial No. 780,188.

To all whom it may concern:

Be it known that I, JOHN W. HUNTER, a citizen of the United States, residing at Englewood, in the county of Jackson and 5 State of Missouri, have invented certain new and useful Improvements in Concrete-Forms, of which the following is a specification.

This invention relates to improvements in 10 concrete forms for sewers, tile, silos and other structures of cylindrical or near cylindrical form, and my object is to provide a form of this character which can be manufactured at small cost and quickly set up for 15 use, or taken down after such use.

In order that the invention may be fully understood, reference will now be made to the accompanying drawings, in which:

Figure 1 is a broken longitudinal section 20 view of the form in use in the construction of a sewer. Fig. 2 is a cross section enlarged, on line II—II of Fig. 1. Fig. 3 is an elevation of a head-block employed in carrying out the invention. Fig. 25 4 is an elevation of an adjustable annulus constituting an important feature of the invention. Fig. 5 is an enlarged broken section of the annulus and gearing for adjusting the same. Fig. 6 is a cross section, enlarged, on line VI—VI of Fig. 4. Fig. 7 is 30 a broken detail perspective of a resilient shell employed in carrying out the invention.

1 designates a shell of cylindrical or substantially cylindrical form and split longitudinally as indicated at 2 to admit of being adjusted diametrically as hereinafter described. Shell 1 being resilient, automatically contracts to its smallest diameter when relieved of pressure, and is provided with 35 a plurality of longitudinal slide-ways 3, which reinforce said shell and form a track for a companion shell or shells to be slid longitudinally through the first-mentioned shell as will hereinafter appear.

45 4 designates an annulus one end of which overlaps the other as shown on Fig. 5, and is provided with a rack-bar 5 intermeshing with a worm 6 fixed upon a shaft 7, journaled in a bearing 8 fixed to said other end 50 of the annulus 4 which is, preferably, made of channel-iron to obtain the requisite strength with the least weight. Both ends of shaft 7 are squared as indicated at 9 to receive a wrench or other tool whereby said 55 shaft and the worm-wheel 6 are rotated to expand or contract the annulus 4.

10 designates a head-block having a circular shoulder 11 to enter and hold one end of the shell 1 in expanded condition. Said head-block 10 is also provided with a peripheral flange 12 which acts as a gage in determining the thickness of the concrete to be applied to the exterior of the shell 1. Head-block 10 is made in two sections, so that it may be expanded or contracted. Said sections have overlapping ends 13 provided with slots 14 to receive bolts 15, which with nuts 16 lock the two sections of the head-block 10 together, after they have been adjusted as desired.

17 designates a plurality of concrete piers which I find convenient to employ as a foundation when the mold is used in the construction of a sewer.

In constructing a sewer, I usually proceed as follows: A number of shells 1 are placed together with lapping ends as shown on Fig. 1. Said shells are laid upon the concrete piers 17 to which they are secured by any suitable means, such, for instance as machine screws 18 which are passed through holes 19 in the shells and screwed into nuts 20 embedded in the piers 17, see Fig. 2. The shells 1 are then expanded to the desired diameter through the intermediacy of one or 25 more annuli 4 after which a head-block 10 is placed in each of the endmost shells 1. The concrete or other plastic mixture A is then placed around the shells 1 and the piers 17, the thickness of the material being 30 gaged by the peripheral flanges 12 of the two head-blocks 10, above-mentioned. After the concrete has become set sufficiently 35 to support its own weight, the form is removed and another section of sewer laid.

One convenient way of removing the form is to allow one of the endmost shells 1 to contract by removing the head-block 10 and annulus 4 therefrom and drawing said shell through the remaining shells on the slide-ways 3, in the direction in which the sewer 40 is to continue. The remaining shells may successively be removed in a like manner.

While I have shown the preferred form of my invention, I, of course, reserve the right to make such changes in the form and construction of parts as properly fall within the spirit and scope of the claims.

Having thus described my invention what I claim and desire to secure by Letters Patent is:

1. In a form of the character described,

a split shell, an adjustable one-piece annulus for expanding and bracing said shell, said annulus being independent of and removable from the shell, and gearing for adjusting said annulus.

2. In a form of the character described, a split shell, an adjustable one-piece annulus for expanding and bracing said shell, said annulus being independent of and removable from the shell, a rack-bar at one end of said annulus, and a worm mounted at the opposite end of said annulus intermeshing with the rack-bar.

3. A form of the character described, consisting of a split shell, an adjustable annulus to expand said shell, an adjustable head-block having a substantially circular shoulder to fit into either end of the split shell,

and a marginal flange on said head-block adapted to project beyond the periphery of 20 the split shell.

4. In a form of the character described, a head-block of two sections having overlapping ends, means to adjustably secure 25 said ends together, a substantially circular shoulder on said head-block, and a marginal flange on said head-block, extending beyond the shoulder to act as a gage or molding surface.

In testimony whereof I affix my signature, 30 in the presence of two witnesses.

JOHN W. HUNTER.
